PHOTOELECTRIC TURBIDIMETER

Peter Schladermundt, Bronxville, John D. Wark, Freeport, and Henry A. Holzwarth, Levittown, N.Y.

Application July 10, 1958, Serial No. 51,721

Term of patent 14 years

(Cl. D52—1)

FIG. 1

FIG. 3

FIG. 2

Figure 1 is a perspective view of a photoelectric turbidimeter, showing our new design.

Figure 2 is a front elevational view thereof.

Figure 3 is an end view thereof.

The undisclosed side is substantially the same in appearance as the side shown, and the rear is plain.

We claim:

The ornamental design for a photoelectric turbidimeter, as shown and described.
